2 Sheets-Sheet 2

Herbert M. Knight INVENTOR

UNITED STATES PATENT OFFICE.

HERBERT M. KNIGHT, OF MONTCLAIR, NEW JERSEY.

SHEET PILING.

Application filed August 10, 1921. Serial No. 491,226.

To all whom it may concern:

Be it known that I, HERBERT M. KNIGHT, citizen of the United States, and resident of Montclair, in the county of Essex and State of New Jersey, have invented certain new and useful Improvements in Sheet Piling, of which the following is a specification.

This invention relates to sheet-piling and has particular application to sheet-piling made of pre-cast concrete.

One of the objects of my invention is to produce a sheet-pile of pre-cast concrete which can be indefinitely extended as conditions may require. Another object of the invention is to produce a sheet-pile of pre-cast concrete which can be jettied to position during the process of driving. Still another object of the invention is to produce a sheet-pile of pre-cast concrete that will, while forming a continuous and tight cofferdam, be so articulated as to be susceptible of considerable flexibility in alinement. Still another object of the invention is to produce a sheet-pile of pre-cast concrete which, when driven in a cofferdam will admit of complete sealing of the joints between piles by the freezing up of the said joints. Still a further object of the invention is to produce a sheet-pile, which, when driven in a cofferdam, will permit of the thawing of a frozen, sealed joint between adjacent sheet piles, for their withdrawal or further driving. Still a further object of the invention is to produce a sheet-pile, which, due to recessed or pocketed faces, will be more easily driven than a plain pile. A further object of the invention is to produce a sheet-pile, which, when located in a cofferdam, will be flexibly connected to other piles by means of keys. Other objects of the invention will appear from the following description and from the accompanying drawings.

The accompanying drawings, Figs. 1 to 15 inclusive illustrate the usual and preferred embodiment of the invention but are not to be considered as inclusive of any and all forms in which the invention may be embodied, nor as exclusive of forms other than those indicated.

I illustrate my invention by the accompanying drawings in which Fig. 1 is a cross-section of a cofferdam at three levels at the points 1—1, 1'—1' and 1"—1" of Fig. 2. Fig. 2 is an interior elevation of two piles

assembled, on the line 2—2 of Fig. 3; Fig. 3 is a longitudinal cross-section of a pile on the line 3—3 of Fig. 2; Fig. 4 is a cross-section of a pile on the line 4—4 of Fig. 2; Fig. 5 is a cross-section at or near the bottom of a pile on the line 5—5 of Fig. 2; Fig. 6 is a longitudinal cross-section of the foot of a pile on the line 6—6 of Fig. 5; Fig. 7 is a plan view of the top of a pile showing the freezing and thawing connections; Fig. 8 is an elevation of the top of a pile on the line 8—8 of Fig. 7; Fig. 9 is an elevation of the bottom section of a key and Fig. 10 is a cross-section of such a bottom key-section, indicating the return bend therein. Fig. 11 is an elevation of a key-section on the line 11—11 of Fig. 13; Fig. 12 a cross-section of a key-section on the line 12—12 of Fig. 13; Fig. 13 a plan view of a key-section on the line 13—13 of Fig. 12; Fig. 14 is a cross-section of a joint between a supporting and a superimposed pile, on the line 14—14 of Fig. 15 and Fig. 15 is an interior elevation of such a joint.

Referring to the drawings in which similar numbers refer to similar parts; 1 is a cofferdam composed of pre-cast concrete piles 2 with pockets 3 in one of their faces and having divisional ribs 4 between the pockets. Shoes 5 with chambers 6 and channels 7 are cast in the bottom of the piles. Ducts 8 are cast in the body of the pile, protruding therefrom below the head of the pile, and joined in manifolds 9. Holes 10 are cast in the divisional ribs. Rebates 11 are cast on the interior edges and chamfers 12 on the exterior corners. Reentrant grooves 13 are cast in the edges of the piles and sectional keys 14 with channels 15 therein are inserted in the alined re-entrant grooves of adjacent piles. The keys are provided with sockets 16 and plugs 17 adapted to secure a driving fit between the sockets and plugs of adjacent key-sections. A return bend 18 is located in the lowest key-section. A source of supply 19 of a freezing compound is connected to one of the channels of the top key-section with regulating means 20 thereon and a discharge means 21 with regulating means 22 is connected to the opposite channel of the top key-section. A lengthening section 23 is superimposed upon a pile. Bolt holes 24 pass through the head 25 of the pile and bolt holes 26 pass through the foot 27 of the lengthening section. Bolts 28 provided with

5 nuts 29 and washers 30 pass through the holes 24 and 26 and fasten the pile and lengthening section together. A slot 31 is cast in the head of the pile and a slot 32 adapted to register with the slot 31 is cast in the foot of the lengthening section. A 10 dam-plate 33 adapted to be located in the slot 31 and to project above the head 25 of the pile and to enter the slot 32 closes the joint between the pile and the lengthening section. Lugs 34 are cast on both sides of the sectional key with a perforation 35 therethrough adapted to permit of the insertion of a wire 36 extending downwardly and engaging an anchor 37 beneath the lug on the bottom sectional key, permitting of the handling and removal of the sectional key as a single unit. Holes 38 pass through the dam-plate engaging mortar in the slots 31 and 32.

15 Sheet-piling, composed of concrete, either plain or reinforced, as usually employed is heavy, difficult to handle, resists driving due to the thickness usually required, and produces an irregular face, due to the lack of any common means of guiding the piles during driving. Again, as it is difficult to form an integral tongue and groove, or similar type of joint, a through joint usually exists without any bulkhead or other ob-

20 structing means therein, permitting the practically unimpeded flow of water through the joint and into the interior of the structure, or cavity surrounded by the cofferdam. These defects limit the success and applica-

25 bility of sheet-piling composed of concrete, as usually produced.

30 The objections and faults above enumerated are corrected in my invention by a number of improvements covering the form and details of the pile, and in connection with its use in conjunction with other and similar piles.

35 In order to overcome the defect of undesirable and unnecessary weight, without decrease in required strength, the inner face of the pile is recessed or pocketed, void producing means being introduced into the forms during the casting of the piles, which produce cavities or depressions upon the face thereof. As a consequence the pile assumes an approximately arched form and becomes thereby stronger, which augmented strength may be still further increased by a disposition of the reinforcement, when the pile is reinforced. The weight of the pile is reduced by the weight of the material represented in the recessed face of the pile, which may, and often does, represent what would have been one half of the weight of a pile of uniform cross-section. This decrease in weight represents not only a very considerable diminution in the amount of material employed but a large reduction in cost as well. But still a further and very important advantage is secured as a result of this

40 pocketing, viz:—the elimination of practically the entire skin friction of the interior face of the pile in the process of driving. The shoe of the pile, or the base thereof in case no shoe is employed, pushes the earth outwardly and consolidates it at the same time, so that a layer of compacted soil surrounds the pile on all sides and presses against all exposed faces thereof, becoming the chief element of resistance to the driving 45 of the pile. But, in the pile herein described, due to the pocketing of one of the faces of the pile, this earth pressure is largely, if not entirely, eliminated on that face, and an easily driven pile results, and one which can be preserved in more accurate alignment during the process of driving. In long piles this recessing of the face might lead to a weak and over limber pile for safe 50 and easy handling, and, for the purpose of meeting this possible defect, and also to provide a means for lifting and handling the pile, cross, or divisional ribs are employed, dividing the recession of the face into a multiple of pockets. Holes in said divisional 55 ribs, or other means therein, are introduced to admit of attaching lifting and handling devices to the pile. As one of the divisional ribs is usually premeditately located slightly above the centre of gravity of the 60 pile, it is at once evident that the transportation, placing and other processes incident to the work of using the pile, is very easily performed.

65 In the process of locating a cofferdam it is often necessary or desirable to place the piling on a circular or irregular line. The ordinary pile, rectangular in section, does not lend itself easily to such circular or irregular formation, as the point of contact of the piles becomes linear rather than superficial, and the corners are liable to either jam or open too wide. In the pile herein described the inner edges are rabbeted from the inner face for a desired distance from 70 the said face. This permits of the pile being arranged on a circular or irregular line without the corners of adjacent piles interfering or being in contact, the piles fulcruming about a point inside of the edges 75 and back of the face, rather than upon the facial corners, as would be the case with an un-rabbeted pile. The outer edges of the pile are chamfered slightly to permit of convexity in the placing of the piles if conditions require such location. In addition to the gain secured in flexibility by the rabbeting and chamfering of the pile arises, a further advantage is secured in the fact that as a slight opening usually exists along the 80 inner edges between the adjacent arises, calking material can be inserted therein to produce water tightness, a highly advantageous provision, especially in cases where it is not desirable or intended to secure such 85

tightness by means of freezing the joint. It is thus seen that the desirable features of articulation, coupled with a means of obtaining tightness, are secured in such sheet-piling with rabbed edges.

In the driving of any form of sheet-piling, especially into soil which is firm or of irregular character, the use of a water jet, in order to break up the cohesion of the soil and to lubricate the passage of the pile, is a desirable practice. This process becomes an especially desirable feature when the piles which are to be driven are of concrete, due to the greater thickness of the piles employed. The resistance resulting from the driving of relatively thick concrete piles into the earth is very great and the force required and the stresses induced in the pile are both extreme and liable to injure the pile while it is being driven. Such force is greatly reduced and such stresses are largely eliminated when a water jet is employed as an adjunct in sinking the pile. The usual practice, when using the water jet, is to attach it in some easily removable manner to the surface of the pile, which it follows downward during the driving of the pile, and which is withdrawn thereafter, and subsequently applied to other piles. Such methods are primitive and consume valuable time in the application of the jet to the pile, in its removal therefrom and in its subsequent attachment to another pile. These objections are met and overcome in the pile illustrated herein by casting the channel carrying the water, either as an enclosed pipe or as a void, in the body of the pile, thereby relieving any necessity for removal or re-application. These pipes or channels terminate in open ends at the foot of the pile, from which the water is discharged with great violence, breaking up and loosening the surrounding earth. As the action of a water jet is largely local, the force or energy of the water being soon dissipated, in bodies of the usual width of the sheet-piling employed it is necessary to use a multiple of such jets. In the illustrated pile these jets are distributed both at the point of the pile and at the back of the bevel so as to secure the maximum effect at the point of greatest resistance. At the top the channels or ducts leave the body of the pile just below the boss of the head, at which point they enter manifolds, flexibly connected with some source of water supply under pressure. While it is entirely feasible to drive sheet-piles of concrete without a special protective shoe, it is found desirable in many instances, especially where the driving is liable to encounter boulders, to provide such shoes of cast iron or similar material, as a protection against disintegration of the bottom of the pile during driving. In the special pile covered in this application the shoe is

perforated and chambered to provide apertures for the discharge of the water jets, such chambers being provided with tight connections for the said jets, by means of screw connections made before the casting of the piles.

As stated above one of the greater objections to the use of concrete sheet-piles is the difficulty of so joining the piling as that the several and adjacent piles shall drive accurately and uniformly. In the pile for which application is hereby made this objection is met and overcome by means of a special joining means, which, while holding the piles in the desired relative and parallel alignment, is sufficiently flexible to permit of the driving of the pile without difficulty or interference. The special type of joining means employed is a key of the "dumb-bell" type, so called, which is adapted to be inserted in alined key-ways or re-entrant grooves cast in the edges of the juxtaposed piles. The re-entrant grooves have a cross-section sufficiently larger than the head of the key to permit a considerable latitude of motion in the adjacent piles without binding or undue stress, the superficies of said grooves being arcs of circles not concentric with the arcs of the superficies of the heads of the keys. These keys are inserted in the grooves while the piles are being set in position and act as guides during the descent of the piles. They furthermore act as bulkheads closing the opening between the piles and materially assist in preventing the infiltration of water.

These keys also perform an additional and very important function in that they become the instrument by means of which it is possible to completely seal the joint between the adjacent piles, absolutely and entirely preventing any leakage through the sheet-piling of the cofferdam. These keys are usually of cast iron and have holes cast in them through the bulb of the key, said holes, except in the case of the lowest key-section, passing entirely through the said key. The keys are made up of a multiple of sections which have sockets on one end and on the opposite ends are plugs slightly larger than and of the same form as the sockets, adapted to secure a driving fit into the said sockets, thus securing a satisfactorily tight union between the key-sections. The lowest key-section, which rests upon the bottom of the re-entrant grooves, is cast with a return bend therein. The top key-section is fitted to receive a double connection to a brine tank as part of a refrigerating apparatus. Brine, at a temperature below that of freezing water, is conveyed down the channel in one side of the perforated key-sections, through the return bend in the bottom key-section and back through the channel on the opposite side of the perforated keys, completing

a circuit, during which, the water surrounding the keys and within the re-entrant grooves is frozen, such freezing completely closing the joint. Subsequently, and when for the purpose of withdrawing the pile or otherwise, it is desired to unseal the joint, steam or hot water is passed through the hollow key-sections melting the ice which surround the keys, thereby making possible the removal of the piles without binding at the joints, a source of great difficulty and expense in the removal of steel sheet-piling. The use of such hollow keys and key-ways is seen to give the desired flexibility of joint with positive positioning, and to provide a perfect means for sealing the joints against infiltration.

When making deep excavations it sometimes becomes imperative to use a longer length of sheet-piling than was deemed necessary or than was provided, such necessity demanding costly additions or undesirable expedients. The usual type of concrete pile or of steel sheet-piling is not adapted to lengthening after it has been located in position. The pile herein illustrated provides in an admirable manner for any and all subsequent increases in length which circumstances or expediency may demand. The head of the pile is cast with a groove or slot therein, adapted to register with a similar slot cast in the foot of the additional length which is to be superimposed thereon, after the location, and possibly after the driving of the bottom pile. A dam-plate is cemented into this slot in the upper section projecting below the foot of the lengthening section so as to enter the slot in the lower section and to be cemented therein, thereby sealing the horizontal joint between the two sections of the lengthened pile. Bolt holes pass through the foot and head respectively of the upper and lower sections and bolts passing therethrough and brought into contact with washers by means of nuts on the said bolts fasten the two sections of the lengthened pile firmly together. Keys, similar to those previously described as employed in the lower section, are inserted in the re-entrant grooves of the upper section, holding the upper section laterally and guiding it in its descent.

What I claim is:—

- 55 1. A pre-cast sheet-pile having a multiple of pockets in the face thereof.
2. A pre-cast sheet-pile having pockets in a face thereof, transverse divisional ribs between said pockets and handling means in said ribs.
- 60 3. A pre-cast sheet-pile, edges to the said pile, re-entrant grooves in said edges, the boundary lines of said grooves being entirely curvilinear.
- 65 4. A pre-cast sheet pile, an outer face to said pile, an inner face, pockets in said in-

ner face, inwardly extending edges, transverse divisional ribs in said inner face extending between said edges, chamfered corners connecting said outer face and said edges, rabbets in the interior corners of said edges and re-entrant grooves in said edges. 70

5. In a structure of the class described, the combination of a multiple of pre-cast sheet-piles, each of said piles having an outer face, an inner face, pockets in said inner face, inwardly extending edges, transverse divisional ribs in said inner face, chamfered corners connecting said outer face and said edges, rabbets on the interior corners of said edges, re-entrant grooves in said edges, said grooves in adjacent piles registering and keys in said registering grooves. 80

6. In a structure of the class described, the combination of a multiple of pre-cast sheet-piles, each of said piles having an outer face, an inner face, pockets in said inner face, inwardly extending edges, transverse divisional ribs in said inner face, chamfered corners connecting said outer face and said edges, rabbets on the interior corners of said edges, re-entrant grooves in said edges, said grooves in adjacent piles registering and sectional keys in said registering grooves. 90

7. In a structure of the class described, the combination of a multiple of pre-cast sheet piles, said piles having an outer face, an inner face, pockets in said inner face, inwardly extending edges, transverse divisional ribs in said inner face, chamfered corners connecting said outer face and said edges, rabbets on the interior corners of said edges, re-entrant grooves in said edges, said grooves in adjacent piles registering, perforated sectional keys in said registering grooves and means connecting said keys 100 with a source of supply of a freezing compound. 105

8. In a structure of the class described, a multiple of pre-cast sheet-piles having inwardly extending edges, registering re-entrant grooves in said edges, perforated sectional keys in said grooves, said sections of said keys having sockets in the tops and plugs in the bottoms thereof. 110

9. In a structure of the class described, a multiple of pre-cast sheet-piles having inwardly extending edges, registering re-entrant grooves in said edges, perforated sectional keys in said grooves, sockets in the tops and plugs in the bottoms of said sections, said sockets and said plugs of adjacent sections being juxtaposed and registering. 115

10. In a structure of the class described, a perforated key composed of a multiple of independent and similar sections, each of said sections having a lug on opposite sides thereof. 120

11. In a structure of the class described, a perforated key composed of a multiple of 130

independent and similar sections, each of said sections having a perforated lug on opposite sides thereof.

12. In a structure of the class described, a perforated key composed of a multiple of independent and similar sections, each of said sections having a perforated lug on opposite sides thereof and means, passing through said perforations in said lugs for handling

10 said keys.

13. In a structure of the class described, a multiple of supporting piles, a multiple of superimposed piles, means positioning said superimposed piles upon said supporting

15 piles, means fastening said superimposed and supporting piles together, each of said piles

having an outer face, an inner face, pockets in said inner face, inwardly extending edges, transverse divisional ribs in said inner face, chamfered corners connecting said outer 20 face and said edges, rabbets on the interior corners of said edges, re-entrant grooves in said edges, said grooves in adjacent piles registering, perforated keys in said registering grooves and means connecting said keys 25 with a source of supply of a freezing medium.

Signed at New York in the county of New York and State of New York this ninth day of August A. D. 1921.

HERBERT M. KNIGHT.
